WILHELM HAMMACHER, OF WIESBADEN, GERMANY.

PROPELLING MECHANISM FOR BICYCLES.

SPECIFICATION forming part of Letters Patent No. 590,413, dated September 21, 1897.

Application filed January 28, 1897. Serial No. 621,060. (No model.)

To all whom it may concern:

Be it known that I, WILHELM HAMMACHER, a citizen of Germany, residing at Wilhelm Strasse 34, Wiesbaden, Germany, have invented certain new and useful Improvements in a Propelling Mechanism for Bicycles, of which the following is a specification.

This invention relates to certain improvements in the means for propelling bicycles.

Heretofore in propelling bicycles the combination of hand and foot power did not produce satisfactory results, for the reason that the steering of the bicycle by the combination of the two powers was rendered less effective.

The object of this invention is to furnish a bicycle in which the propulsion is accomplished by hand and foot power without impairing the easy steering of the bicycle; and the invention consists in the propelling device for bicycles to be hereinafter described, and finally pointed out in the claims.

In the accompanying drawings, Figure 1 represents a side elevation of my improved bicycle. Fig. 2 is a front elevation of the same. Fig. 3 is a plan of the front part; Fig. 4, a detail vertical transverse section of the double bevel gear-wheel on the front fork and the connections of the same with the adjacent parts. Fig. 5 is a plan view of the lower half of the double bevel-wheel. Fig.

6 is a vertical transverse section showing a modified form of the motion-transmitting double bevel gear-wheel on the front fork, in which the wheel is shown of one piece. Fig.

7 is a side elevation of the clutch mechanism used in connection with the double bevel gear-wheel. Fig. 8 is a plan view of Fig. 7, partly in section. Fig. 9 is a sectional view showing the stop mechanism, and Fig. 10 is the stop-

pin of the same.

Similar letters of reference indicate corresponding parts.

Referring to the drawings, *a a'* are the handle-bars, which turn on a horizontal shaft *A*. This shaft is supported in journal-bearings at the upper ends of two inclined braces *b b'* and also in bearings of the upper end of the horizontal stop-rod *c*, as shown in Fig. 3. On the front fork is arranged at the left-hand side a bevel gear-wheel *d*, which is keyed to a shaft *D*, journaled in the fork and which

is operated by a connecting-rod *e*, that is hinged at its upper end to one of the handle-bars *a* and connected at its lower end with a crank-pin *e* on the bevel gear-wheel *d*, and which bevel-wheel is set in rotary motion by the raising or lowering of the handle-bar *a*. At the opposite end of the shaft *D* is applied a crank *f*, which is shown in Figs. 2, 3, and 6 and which is arranged at an angle of one hundred and twenty degrees to the crank-pin *e* on the bevel gear-wheel *d*. The crank *f* is connected by a connecting-rod *e'* with the second handle-bar *a'*, as shown in Fig. 3.

For transmitting the rotary motion of the bevel gear-wheel *d* to the sprocket-wheel on the rear axle, from the spindle of the front fork, without impairing the steering capacity of the bicycles a bevel gear-wheel *H* is arranged, as shown in Figs. 1, 2, and 3, on the spindle so that it can freely turn around the same. This bevel gear-wheel *H* can either be made solid in one piece and provided with a double bevel-gear arranged at suitable angles of inclination to each other, as shown in Fig. 6, or it can be made of two sections *h h'*, as shown in Figs. 4 and 7, which are locked together by a suitable clutch mechanism and which forms the main novel feature of my invention. The geometrical center of the bevel gear-wheel *H* is located in line with the axis of the spindle of the front fork of the bicycle. When the bevel gear-wheel *H* is made of two sections *h h'*, an inverted cone *p* is screwed upon the spindle *l* of the front fork, as shown in Fig. 4, and provided in its upper surface with an annular groove, in which antifriction-balls, that serve for the support of the upper half *h* of the double bevel gear-wheel, are supported, while on the upper side of the bevel gear-wheel *h* a collar *i*, that is secured to the spindle *l*, prevents the double bevel gear-wheel *H* from moving in upward direction. Between the upper half *h* of the bevel gear-wheel *H* and the stop-collar *i* are again arranged a number of antifriction-balls, which reduce the friction between these two parts.

The lower section *h'* of the double bevel gear-wheel *H* rests on a clutch-ring *q*, between which and the lower section *h'* is arranged a third series of antifriction-balls.

By the clutch-ring q the lower section h' of the double bevel gear-wheel H can be interlocked with the upper section h or removed from the same, so that the parts are either placed in or out of mesh, whereby the power of the arms of the rider can be either transmitted or not, as required.

The double bevel gear-wheel H being arranged loosely on the spindle of the front fork and movable on the same has a perfectly smooth and easy motion owing to the arrangement of the antifriction-balls between the different parts and permits the unimpeded turning of the front fork and its spindle. Instead of the clutch-ring q a supporting-collar q' is used in the modification shown in Fig. 6. The double gear-wheel H serves to transmit the power exerted by the arms of the rider on the handle-bars $a a'$ from the front part to the rear part of the bicycle, inasmuch as the lower section h' of said double bevel gear-wheel meshes with the bevel gear-wheel d , while the upper section of the double bevel gear-wheel H meshes with the teeth of a small pinion m , which is arranged at the upper end of a tubular shaft m' , that turns in bearings of the frame F and which carries at the lower end a pinion n , which meshes with a bevel gear-wheel n' on the sprocket-wheel o of the crank-shaft.

By the arrangement described the power of the arms, as well as the power of the legs, is transmitted to the sprocket-wheel o , from which both powers are transmitted by the usual sprocket-chain and sprocket-wheel to the rear wheel.

For permitting and facilitating the use of the hand-power the double bevel gear-wheel H is, as before stated, preferably divided into two parts $h h'$. These two parts are provided at their circumference with bevel-teeth and are coupled by means of three ribs r , which are arranged on the lower section h' and which engage three corresponding recesses in the adjacent surface of the upper section h , as shown in Figs. 4 and 5. The ribs r , as well as the recesses with which they engage, are made of triangular cross-section at the points of contact with each other.

When the clutch-ring q is lowered, the section h' is compelled, by means of the angular connecting-pins h^2 , to follow this motion, whereby the ribs r are removed from the corresponding recesses in the upper section h , so that the upper section of the double bevel gear-wheel remains stationary even when the lower section h' continues its rotary motion. The lower section h' is annularly grooved at its interior, so that the pins h^2 , which project thereinto, will permit the rotation of said section.

For avoiding any unnecessary motion when the hand-power is not to be used a stop device is provided which is only called into action when the two handle-bars are on a level with each other. For this purpose the bevel

gear-wheel d is provided with a hole d' at its rear side, which is engaged by one end of a stop-pin y , as shown in Figs. 8, 9, and 10, as soon as the clutch-ring q is lowered, so that not only a further rotary motion of the double bevel gear-wheel, but also the oscillating motion of the handle-bars connected therewith for imparting a propelling motion to the bicycle, is prevented.

The motion of the clutch-ring q and the motion of the stop-pin y connected therewith are accomplished by the lever-rod s , which is connected at t rigidly with the horizontal fork u . In the ends $u' u^2$ of the fork u is suspended a clutch-ring q , so that the same can move in upward and downward direction, as well as slightly in sidewise direction, following the natural pressure of the intermeshing bevel-wheels d and H . The lower section h' of the double bevel gear-wheel H has during its uncoupling motion from the upper section h a downward-inclined motion, during which it is partly guided by the inverted cone p . The fork u of the clutch-ring q permits the twofold motion just described in downward direction, as it is supported on a vertical pivot-pin w , located on a rock-shaft v , which turns by its pivot-pins in bearings of the inclined braces $b b$, as shown clearly in Fig. 8. The lower section h' of the double bevel gear-wheel H is not withdrawn entirely from the teeth of the bevel-wheel d , but slides merely along the same to some extent in downward direction. By this arrangement it is possible to return the lower section h' when it is to be coupled with the upper section h to the former position toward the bevel-wheel d , as well as toward the upper section h , which position it had before the uncoupling, or, in other words, the position of the handle-bars remains in the same harmonic relation to the cranks before and after the coupling and uncoupling of the sections $h h'$ of the double bevel gear-wheel H .

At the lower end of the rod s is arranged a rock-arm s' , which is connected with the angle-lever x' , that turns on a fixed pivot x . The angle-lever x' has an enlargement or bulge x^2 , which engages a recess of the stop-bolt y , so as to compel the same to follow its motion. When the lower section h' of the double bevel gear-wheel H is uncoupled, the upward motion of the rod s produces the motion of the lower end of the latter, so that the arm s' is rocked, which thereby moves the angle-lever x' in forward direction, whereby the engagement of the stop-pin y in the hole d' is produced as soon as the latter is located opposite to the same. The stop-pin y is actuated by means of a helical spring, as shown in Fig. 9, the tension of which acts on the mechanism connected therewith mainly by pressing the lower section h' of the bevel-wheel H against the upper section h if the former is not pressed by the lever-rod s in lateral and downward direction.

Having thus described my invention, what I claim as new, and desire to secure by Letters Patent, is—

anism for coupling the two sections of the double wheel together or for uncoupling them, 40 substantially as set forth.

1. In propelling mechanism for bicycles, the combination with fulcrumed handle-bars, of a double gear-wheel sleeved on the front fork, a gear-wheel located on the front fork and below said double gear-wheel and meshing with the lower series of teeth of the double gear-wheel, means for connecting said latter gear-wheel with the handles, for turning the latter, a shaft provided with a pinion meshing with the upper series of teeth of the double wheel, and means for transmitting motion from the said shaft to the driving-wheel, substantially as set forth. 45

2. In propelling mechanism for bicycles, the combination with fulcrumed handle-bars, of a double gear-wheel sleeved on the front

fork, a gear-wheel located on the front fork and below said double gear-wheel and meshing with the lower series of teeth of the double wheel, and driven directly from the han-

5 double wheel, a pinion meshing with the upper se-

25 ries of teeth of the double wheel, and mounted on a shaft journaled in bearings of the main

frame, a bevel gear-wheel on the rear end of

30 said shaft, and an intermeshing bevel gear-

wheel on the pedal-shaft of the foot driving

35 mechanism, substantially as set forth.

3. In propelling mechanism for bicycles,

the combination with the double bevel gear-

40 wheel consisting of two suitably-mounted and

independent sections each having a series of

45 bevel-teeth, mechanism for rotating the wheel

from the handle-bars, and means for trans-

50 mitting motion from the double wheel to the

driving-wheel of the bicycle, of a clutch mech-

55

anism for coupling the two sections of the

double wheel together or for uncoupling them, 40

substantially as set forth.

4. In propelling mechanism for bicycles,

the combination with a double bevel gear-

50 wheel consisting of two independent toothed sec-

tions mounted on the front fork and adapt-

45 ed to be interlocked, mechanism for rotating

said double wheel from the handle-bars, and

means for transmitting motion from the dou-

50 ble wheel to the driving-wheel of the bicycle,

of a clutch-ring for withdrawing the lower 50

section from the upper section of the double

wheel, and a rod connected with the clutch-

55 ring and extending upward toward the han-

dle-bars, substantially as set forth.

5. In propelling mechanism for bicycles,

the combination with a double bevel gear-

55 wheel formed of two independent toothed sec-

tions adapted to be coupled, mechanism for

rotating said double wheel from the handle-

bars, and means for transmitting motion from

60 the double wheel to the driving-wheel of the

bicycle, of a hand-operated rod, means for

connecting the same with the lower section

65 of the double wheel and a stop-pin operated

by said rod, and adapted to lock the handle-

bars in their intermediate position for the

purpose of holding them there when the hand-

power has been removed, substantially as set

forth.

In testimony that I claim the foregoing as

70 my invention I have signed my name in pres-

ence of two subscribing witnesses.

WILHELM HAMMACHER.
